INVENTOR

Harry E. Townsend.

UNITED STATES PATENT OFFICE.

HARRY E. TOWNSEND, OF BROOKLYN, NEW YORK.

CLOSURE.

1,404,913.

Specification of Letters Patent. Patented Jan. 31, 1922.

Application filed January 30, 1919. Serial No. 274,071.

To all whom it may concern:

Be it known that I, HARRY E. TOWNSEND, a citizen of the United States, and a resident of New York, borough of Brooklyn, 5 and State of New York, have invented certain new and useful Improvements in Closures, of which the following is a specification, reference being had to the accompanying drawings, which form a part thereof.

10 The object of my invention is to provide a closure for containers for food products and the like, with a narrow sealing ring or gasket so placed as to form a seal on the inside of the mouth of the container at a 15 distance from the top thereof and by the lateral compression of the gasket between the mouth of the container and a depending portion of the closure, and to form such a closure with effective means for removing it 20 from the container. The advantages which I have in view are the saving of closure and gasket material incident to the formation of the seal on the inside as contrasted with the outside or top of the container and the 25 use of a narrow gasket, the avoidance of the risk of buckling the gasket which would exist if a wide gasket were used; the formation of a thoroughly satisfactory seal depending solely or mainly on the lateral compression of the gasket; the ready removal 30 of the closure and its capacity to form a good seal even when not under pressure due to a vacuum in the container.

With these objects in view I form a closure normally and preferably of glass or vitreous material, having preferably a flanged top adapted to extend over the mouth of the container and formed with a gasket holding annular shoulder at some 35 distance from its union with the top portion, and I fit a narrow gasket, preferably of rubber, on said depending portion below and against the shoulder formed thereon. This closure is designed to be used with a container having a mouth which contracts from 40 the top downward, and preferably with one in which the contracted portion merges with a cylindrical portion so located that the gasket will lie entirely against such cylindrical portion when the closure is fully inserted into the container mouth, and my invention 45 consists in the described closure and in the combination with such a closure of the described container. While my improved closure will form a good seal without it I 50 further provide for an abutment in the con-

tainer mouth against which the gasket rests, when the closure is fully inserted and which serves the double purpose of providing a sealing surface on the under side of the 60 gasket and serving as a limit stop, determining how far the closure shall pass down into the container mouth.

My invention will be best understood as described in connection with the drawings 65 in which it is illustrated and in which

Figure 1 is a side elevation, partly in section, showing my closure applied to a suitable container.

Figure 2 is a similar partly sectional elevation showing my closure applied to a specially formed container with an external shoulder.

Figure 3 is a partly sectional elevation showing a modified form of my closure and 75 a container mouth of bottle like character.

Figure 4 is an enlarged sectional view of a portion of the closure and container shown in Figure 1, with the closure in the act of being inserted in the container.

Figure 5 is a similar sectional view showing the container fully inserted.

Figure 6 is a similar sectional view showing a modified form of container.

Figure 7 is a similar sectional view showing still another modified form of container, and

Figure 8 is a view similar to Fig. 1, but showing the closure top formed with a 85 plugged opening.

Referring first to the construction shown in Figs. 1, 4 and 5, 19 indicates the container which is here formed in tumbler shape, with a mouth inwardly tapered at the edge as indicated at 14, the tapering portion merging into a straight portion 15. The closure indicated in the above figures, and also in Figs. 6 and 7, as indicated at 10, and is formed with an annular projecting flange 17, which extends over the mouth of the container, as shown, and formed also with a downwardly extending cylindrical portion 18 adapted to enter the mouth of the container, and of such diameter at its upper portion that its edge will approach quite 100 closely to the straight portion of the container mouth. The lower portion of the downward extension of the closure is formed of smaller diameter as indicated at 11, so that a gasket seat 13 is formed on the downward projection of the closure at some distance from its flange 17, and preferably, at 110

such a distance that the gasket fitted on the portion 11, and against the shoulder 13, will, when the closure is inserted in the container, fit against the straight portion 15 of the container.

In Fig. 2 the container here shown is of jar form and indicated by 20, is generally similar with regard to formation of its mouth to the container shown in Fig. 1, except that below the straight portion 15 of the closure mouth the annular seat 16 is formed against which the gasket 12 is pressed when the closure is in fully inserted position.

In Fig. 6 a modified form of container is shown generally similar to that shown in Fig. 1 and indicated at 21, but having a rounded internal lip indicated at 23 instead of the conical lip indicated in Fig. 1. In Fig. 7 still another form of container is indicated at 22, the mouth of which is formed by a continuously inclined surface as indicated at 24. In Fig. 3 the container, here indicated as of bottle form, is marked 19^a and has its mouth formed as in Fig. 2. The closure is shown as having a head 18 which does not extend over the top of the container and it is also shown with a prolonged narrow cylindrical portion 17 extending well into the mouth of the bottle below the gasket 15 and serving to prevent the tipping of the closure in the bottle neck.

In operation the parts are assembled as indicated in Figs. 4 and 5. A narrow gasket 12 is inserted on the reduced portion 11 of the projection 18, so as to rest against the shoulder 13 and project for an appropriate distance beyond the depending portion 18. In use the closure is brought to position over the container, as indicated in Fig. 4, and forced down to the position indicated in Fig. 5, the gasket being compressed in passing over the inclined surface 14 and held in compressed condition against the straight portion 15. By preference, and as shown, the gasket 12 is of a thickness somewhat less than the length of the narrow cylindrical part 11 on which it rests, so that when thickened up by compression, as shown in Fig. 5, it will not extend below the edge of part 11. In Fig. 8 the closure is shown as having a small hole in it filled with a plug 20, which can be perforated or punched in to relieve the pressure and make it easier to remove the closure.

The operation of the closure in connection with the modified form of container shown in Figs. 5 and 6 is obvious, and the operation of the closure in the construction shown in Fig. 2 involves the compression of the gasket, not only against the portion 15 of the container mouth, but also against the shoulder 16.

It will be very obvious to those skilled in the art that my construction is one especially

well adapted for the sealing of containers under a vacuum, and it will also be obvious that my construction involves the minimum consumption of material used for making the closure and the gasket, and I would call special attention to the fact that my closure 70 enables a narrow gasket to be used with much better results than would be obtainable with a broad gasket, because in view of the small size of the gasket it is not liable 75 to buckle or kink while being inserted, but is compressed and held in position evenly at all points of its circumference.

It will be very obvious that my closure, as shown in all Figs. except Fig. 3, can be 80 readily removed from the container by insertion of a convenient tool, such as a knife blade, between the top of the container and the flange 17 of the closure and after removal the closure is well adapted for renewed use in connection with the container.

Having now described my invention, what I claim as new and desire to secure by Letters Patent, is:

1. A sealing closure for containers comprising an annular outwardly extending flange adapted to extend over the mouth of the container, a downwardly extending cylindrical portion adapted to enter freely the mouth of a container for a considerable 95 distance and having a downward cylindrical extension of less diameter and an annular shoulder formed between the broader and narrower portions of said cylindrical portion to form an abutment for a gasket 100 fitted on the narrower cylindrical portion, in combination with a narrow compressible gasket fitted against said shoulder and a container having a mouth contracting from the top inwardly in such manner as to compress the gasket laterally as the closure is pushed down therein, said contracted portion extending for a distance not substantially greater than the length of the downwardly extending portion of the closure 110 above the gasket, said container mouth having also below said contracted portion a lateral seating surface for the compressed gasket so formed as not to substantially affect the compression of the gasket as it 115 moves over it.

2. A sealing closure for containers having an annular outwardly extending flange adapted to extend over the mouth of the container, a downwardly extending cylindrical portion adapted to enter freely the mouth of the container for a considerable distance and having a downward extension of less diameter and an annular shoulder formed between the broad and narrow portions of said extension at a distance from the top of the closure, said shoulder being adapted to form a seat for a narrow gasket fitted on the narrower portion of said extension and a narrow compressible gasket 130

fitted against said shoulder, in combination with a container having a mouth contracting from the top inward for a distance not substantially greater than the length of the 5 downwardly extending portion of the closure above the gasket, and below said contracted portion of cylindrical form so as to compress the gasket laterally as the closure is forced into the container mouth and furnish a cylindrical surface holding the gasket in compressed condition when the closure is 10 fully inserted.

3. A sealing closure for containers comprising a head adapted to extend above the 15 container mouth, a downwardly extending cylindrical portion adapted to enter freely the mouth of a container for a considerable distance and having a downward cylindrical extension of less diameter and an annular shoulder formed between the broader and narrower portions of said cylindrical portion to form an abutment for a gasket 20 fitted on the narrower cylindrical portion in combination with a narrow compressible 25 gasket fitted against said shoulder, and a container having a mouth inwardly flared at its upper end so as to compress the gasket laterally as the closure is forced into the container mouth and a shoulder formed below 30 said inwardly flared end to form a seat

for the compressed gasket when the closure is inserted.

4. A sealing closure for containers having an annular outwardly extending flange adapted to extend over the mouth of the 35 container, a downwardly extending cylindrical portion adapted to enter freely the mouth of the container for a considerable distance and having a downward extension of less diameter, and an annular shoulder 40 formed between the broad and narrow portions of said extension at a distance from the top of the closure, said shoulder being adapted to form a seat for a narrow gasket fitted on the narrower portion of said extension, and a narrow compressible gasket 45 fitted against said shoulder, in combination with a container having a mouth contracting from the top inward for a distance not substantially greater than the length of the 50 downwardly extending portion of the closure above the gasket, and below said contracted portion of cylindrical form terminating in an annular shoulder so as to compress the gasket laterally as the closure is 55 forced into the container mouth and furnish a cylindrical surface and abutting shoulder holding the gasket in compressed condition when the closure is fully inserted.

HARRY E. TOWNSEND.
